US00D473597S

(12) **United States Design Patent** (10) Patent No.: **US D473,597 S**
Clark (45) Date of Patent: **** Apr. 22, 2003**

(54) **ELECTRONIC GAME APPARATUS**

(75) Inventor: **Scott Clark, Wilbraham, MA (US)**

(73) Assignee: **Hasbro, Inc., Pawtucket, RI (US)**

(**) Term: **14 Years**

(21) Appl. No.: **29/163,300**

(22) Filed: **Jul. 1, 2002**

(51) LOC (7) Cl. **21-01**

(52) U.S. Cl. **D21/329**

(58) Field of Search .... **D21/324, 328, D21/329, 330, 333; D14/400, 401, 496; 273/148 B; 463/1, 29-35, 46, 47**

(57) **CLAIM**

The ornamental design for an electronic game apparatus, as shown.

DESCRIPTION

FIG. 1 is a perspective view of the electronic game apparatus of the instant invention;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.
